WINDOW STOP

Raymond W. Schemansky, Detroit, Mich.

Application August 1, 1946, Serial No. 687,802

1 Claim. (Cl. 292—194)

1

My invention relates to a new and useful improvement in a window stop adapted for mounting in conjunction with a pair of slideable sashes to provide means for either securing said sashes in fixed relation when in closed position or permitting said sashes to be relatively moved a predetermined distance.

It is an object of the present invention to provide a window stop of this class which will be simple in structure, economical to manufacture, durable, easily and quickly operated, highly efficient in use, and readily installed.

Another object of the invention is the provision of a window stop of this class which may be used for limiting slideable movement of a pair of window sashes relative to each other to a predetermined degree or which may be moved to position for preventing movement of either of the sashes out of closed position.

Other objects will appear hereinafter.

It is recognized that various modifications and changes may be made in the detail of structure illustrated without departing from the invention and it is intended that such shall be embraced within the scope of the claim which forms a part hereof.

Forming a part of the specification are drawings in which,

Fig. 1 is a side elevational view of the invention showing it applied and illustrating the window sashes in closed position,

Fig. 2 is a view similar to Fig. 1, illustrating the window sashes moved relatively to each other out of closed position,

Fig. 3 is a side elevational view of the invention showing it applied and in use as a securing member for securing the window sashes against relative movement from closed position.

Fig. 4 is a sectional view taken on line 4—4 of Fig. 2,

Fig. 5 is a sectional view taken on line 5—5 of Fig. 1, with parts broken away and parts shown in section.

In the drawings I have shown the invention applied in connection with a pair of window sashes 9 and 10 which are slidably mounted in a window frame 11. Mounted on the vertically extending side rail 12 of the upper sash is a metal plate 13 having one edge turned to provide a flange 14 which extends inwardly toward the pane of glass 25 and which terminates in spaced relation to the inner face of the pane of glass 25. The end of the plate 13 is turned inwardly to provide a flange 15 which serves as a stop.

Mounted on the upper rail 16 of the lower sash

is a metal plate 17 having the upwardly projecting flange 18 in which is formed the bayonet slot 19. The metal plate 20 is provided with the rivet 21 which rides in the slot 19. This plate 20 is angularly turned at its end to provide the angularly turned portion 22 which is again angularly turned to provide the doubled over portion 23. The end of the plate 20 is provided with a V notch 24.

10 When the parts are mounted as shown in the drawings a plate 20 may be swung either to the dotted line position or to the full line position shown in Fig. 1. When swung to the full line position the plate 20 is in operative position and 15 is in such a position that the angularly turned portion 23 will engage behind the flange 14 as clearly shown in Fig. 4. When in this position the sashes may be moved relatively to each other and when the lower sash is raised the flange 23 20 will ride behind the flange 14 until the abutment or stop plate 15 is engaged by the flange 23. When this engagement is effected the sashes can be moved no farther and, consequently, there is thus provided a means for limiting a relative 25 movement of the sashes from closed position so that it becomes possible to open the window at night and leave it partially open with the assurance that it cannot be opened further. When it is desired to render the device inoperative the 30 plate 20 will be swung to the dotted line position shown in Fig. 1, and the sashes then may be moved relatively to each other without interference from the mechanism mounted thereon.

It will be noted that in these positions the rivet is occupying the end of the slot 19. When the plate 20 is moved to the left of Fig. 2, so that the rivet reaches the end of the slot 19 it will engage in the recess 27 and when in this position it may be moved to the position shown in 40 Fig. 3 so as to engage the lower edge of the plate 13 and thus serve as a means for securing the windows in fully closed position and preventing their relative movement from closed position.

The invention is one which may be very inexpensively manufactured, which is durable and which has proven itself most efficient in use.

What I claim is:

A window stop adapted for use with a pair of relatively movable window sashes, one of said sashes being a lower sash and the other an upper sash and said upper sash having a vertically extending side rail and said lower sash having a horizontally extending top rail and a pane of glass in said upper sash positioned outwardly 50 from said side rail, said stop comprising: an elongated

gated, vertically extended plate mounted at one edge on the face of said side rail; an angularly turned, longitudinally extending flange along the opposite edge of said plate, turned inwardly toward said pane of glass and spaced therefrom; an abutment flange on the upper end of said plate and turned inwardly toward said glass and spaced therefrom; a bracket mounted on the upper face of the top rail of the lower sash and having a longitudinally directed slot formed therein provided with a notch at one end; a swingable plate; a pin pivotally mounting said swingable plate on said bracket, said pin slidably engaging in said slot and being movable in said slot for engaging in said notch; a doubled-over flange on the free end of said swingable plate terminating in spaced relation to the main body of said swingable plate to provide a space for receiving said first-named flange upon relative movement of said sashes a predetermined distance from closed position, and adapted for engaging said abutment upon

further relative movement of said sashes from closed position, said swingable plate having a notch formed in its free end engageable with the lower edge of said vertically directed plate upon engagement of said pin in the notch of said slot for preventing relative movement of said sashes from closed position.

RAYMOND W. SCHEMANSKY.
